I. M. CUTLER.

REFRIGERATOR.

APPLICATION FILED MAR. 15, 1917.

1,290,772.

Patented Jan. 7, 1919.

UNITED STATES PATENT OFFICE.

ISABELLA M. CUTLER, OF NORTH GLENDALE, CALIFORNIA.

REFRIGERATOR.

1,290,772.

Specification of Letters Patent.

Patented Jan. 7, 1919.

Application filed March 15, 1917. Serial No. 155,075.

To all whom it may concern:

Be it known that I, Mrs. ISABELLA M. CUTLER, a citizen of the United States, residing at North Glendale, in the county of Los Angeles and State of California, have invented new and useful Improvements in Refrigerators, of which the following is a specification.

My invention relates to refrigerators and more particularly to attachments for ice-boxes or refrigerators; and the objects of my invention are, to save ice or use less ice for refrigeration in ice-boxes; to provide an automatic cooling apparatus without having to use ice or any chemicals; to provide an automatic cooling apparatus which will prevent ice, if such is placed into the refrigerator, from rapid melting; to provide a cooling apparatus in form of hollow walls attachable to the inside or to the outside of common refrigerators; to provide an automatic cooling apparatus which is operated by taking water from any faucet in the house in which such refrigerator is in use; the invention consisting in the construction, combination and arrangement of devices hereafter more fully described and claimed, and illustrated in the accompanying drawing, in which—

30 Figure 1 is a vertical cross-section of a portion of my device.

Fig. 2 is a vertical longitudinal section through the water circulating compartment of my device.

35 Fig. 3 is a side view of a thermostat for procuring an automatic circulating of the water in my device.

Fig. 4 is a side elevation of the thermostat connected at one end to the operating lever of the auxiliary operating valve of the device, the thermostat being connected or held at the other end to the casing or any other suitable place near the casing.

45 Fig. 5 is a vertical cross sectional view of a refrigerator with a number of my devices in place within the refrigerator.

Fig. 6 is a front elevation of a refrigerator with a number of my devices applied to the outside.

50 Referring to the drawing, 1 designates a casing which is a part of my device attachable to the sides of a refrigerator, inside or outside of the refrigerator, the flanges 2 being provided for attaching such casing of my device to the walls of the refrigerator.

Each of these casings is subdivided by a partition 3, forming the water circulating compartment 4 and the air compartment 5. A connection 6 is provided to be attached to the water supply pipe in a building. A suitable number of baffle-plates 7 are disposed in the upper part of the water circulating compartment to deflect and direct the course of the water for a suitable circulation, and, secured to the outlet opening 8 in the lowermost baffle-plate, is a nozzle 9 discharging the water into the buckets 10 of a small water wheel 11 mounted on a shaft 12 within the lower part of the water circulating compartment, thereby setting this wheel in motion. An outlet connection 13 is provided at a suitable place at the opposite side of the water compartment.

This outlet connection is provided to be attached to the water pipe in a building before any of the valves and faucets in the building, so as to cause the water used in the house and taken from the several valves and faucets in the house to pass through the water circulating compartment in each of the casings in my device, thus causing an automatic circulating of the cool water from the main water supply pipe in the house through my device, whenever any of the valves and faucets in the building are opened.

55 In case that the house is closed during the day time or for any length of time during which no water is used and naturally no water caused to circulate through my device, I provide a thermostat at a suitable place in the outlet pipe, in the drawing, a T-connection 14 being shown having a pipe connection 15 to which a valve 16 is secured. A turning stem 17 is mounted in the valve 16, being provided with an operating lever 18 for turning the stem. A port 19 in the stem is provided to come into alignment with the conduit 20 in the pipe 15 by the proper turn on the lever 18. Connected to the lever 18 is a thermostat by a suitable connection 21, allowing the turning of the lever. At the other end, the thermostat is provided with a plate 22 or other suitable connections to be secured to the casing in my device or to the walls of the refrigerator. The thermostat itself is preferably made of one or more layers of hard rubber 23 and one or more layers of metal 24, both layers interconnected by rivets 25 or other suitable means, the rubber layers, being shown in the drawing on

the outside, normally expanding and contracting before the metal layers, will naturally cause the opening of the arch-shaped thermostat while the rubber is contracting and becoming shorter (in proportion) than the metal layers, and, an increasing of the heat in the refrigerator, causing the expansion of the layers, will naturally bring the ends of the thermostat closer as the rubber expands more than the metal. Having this thermostat connected to the lever 18, it will be understood that the valve 16 can be opened automatically by the increasing heat in the refrigerator. The end 26 of the valve 16 is connected to the drain or sewer in a building, allowing the water to flow off and allowing fresh cool water to pass through the water compartment in my device. The end 27 of the outlet pipe 13 is connected to the water pipe in the building before the valves and faucets in the building.

In Fig. 4, the arch-shaped thermostat is illustrated in contracted position as indicated at 33, bringing the lever 18 to the position indicated at 34, which would naturally have to be the open position of the valve 16 after the description above. The expanded position of the thermostat indicated at 35 brings the lever 18 to the position indicated at 36, which is naturally the closed position of the valve 16 as will be understood from the description above. The thermostat arranged in this manner naturally controls the flow of water through any number of my devices disposed in or at a suitable place or position to a refrigerator by causing the water to pass through the port 19 in the valve 16 whenever the thermostat is influenced in the manner described above by the temperature in or near the refrigerator, as will easily be understood.

In the air compartment 5 of my device, I mount a fan 28, in the drawing the fan being shown mounted directly on the shaft 12 of the water wheel, but it will easily be understood that a chain or gear connection can be provided to cause the fan to revolve more rapidly than the water wheel. An opening 29 is provided in the casing allowing air to pass through the fan into the air compartment 5 promoting the cooling in my device. Another means for promoting the cooling is a small overflow pipe 31 allowing but a dripping of water from the water compartment into the air compartment on to a burlap or copper screen 32 disposed at a suitable place above the fan.

The passing of cool water through the compartment 4 naturally already produces a cooling effect to a certain extent, this is increased by the air circulation through the compartment 5, the air being drawn into the compartment 5 through the opening 29 through the fan 28 and out of the compartment through the openings 30. To further-

more increase the cooling effect, the small overflow pipe 31 is provided, allowing water to escape out of the water circulating compartment 4 for dripping down to the burlap or screen 32 against the draft and air circulation through the compartment 5, the air passing through the dampness produced by the leaking of water from the compartment 4 into the compartment 5 increasing the cooling effect considerably.

From the description above it will be understood that the device consists mainly of a casing having a water circulating compartment and also an air circulating compartment, the circulation in either compartment being produced automatically by compelling water to pass through the device whenever any water is being used or taken out of any valve or faucet in a house or any place where this device is in operation, or, the circulation being produced automatically by the operation of the thermostat described above.

It will also be understood from the above description that devices of this kind, otherwise called casings, can be disposed at any place where a cooling is desired, inside of a refrigerator to the sides 37 the rear 38 the top 39 and the bottom 40 as illustrated in Fig. 5, or outside of a refrigerator to the sides 41 the top 42 and the door 43 as illustrated in Fig. 6. When securing or applying a casing to the door of a refrigerator, any pipes or other connections with the casing have, of course, to be provided with a union joint indicated at 44, as will easily be understood, to allow the opening or turning of the door on the hinges. The casing are secured to any place where they are desired by any suitable means, nails, screws, or any other suitable means as indicated at 45, such means will be known to any person without being illustrated.

I claim:

1. In a refrigerator a casing having a partition forming a water circulating compartment and an air circulating compartment, a suitable number of staggered baffle-plates being provided in the water circulating compartment extending from one side of the casing, one beyond the other toward the opposite side, a suitable space between the innermost baffle-plate and such opposite side of the casing for a wheel compartment, a water wheel being disposed in the wheel compartment, a nozzle being provided on the innermost baffle-plate pointing toward the water wheel for directing the water passing through the water circulating compartment between the several baffle-plates toward the wheel for turning the wheel, and a fan being disposed in the air circulating compartment operatively connected to the water wheel.

2. In a refrigerator of the class described

a casing having a water circulating compartment and an air circulating compartment, a water wheel being disposed in the water circulating compartment, a fan being disposed in the air circulating compartment operatively connected to the water wheel, and water overflowing means provided between the water compartment and the air compartment in the path of the air draft 10 through the air circulating compartment.

3. In a refrigerator of the class described having water and air circulating compartments, a water overflowing means communicating with the water circulating compartment terminating within the air circulating compartment, and screening means disposed in the air circulating below the water overflowing means in the path of the air circulation through the air circulating compartment.

4. In a refrigerating device of the class

described the combination of a water overflowing means and a screen disposed so as to allow the water from the overflowing means to drip on to the screen in the path 25 of the air circulation in such device.

5. In a refrigerator of the class described a casing having a water circulating compartment and an air circulating compartment, a water wheel being disposed in the 30 water circulating compartment, a fan being disposed in the air circulating compartment operatively connected to the water wheel, and a thermostat connected to the water supply for automatically controlling the 35 flow of water through the device.

In testimony whereof I hereunto affix my signature in the presence of two witnesses.

Mrs. ISABELLA M. CUTLER.
